CLUTCH AND BRAKE FOR GRINDING APPARATUS

Robert E. Allen and William F. Utzinger, Dayton, Ohio, assignors to The Univis Lens Company, Dayton, Ohio, a corporation of Ohio

Application March 20, 1948, Serial No. 15,994

1 Claim. (Cl. 192—18)

1 This invention relates to lens grinding apparatus for processing lens blanks, and more particularly to improvements in the construction of high-speed lens grinders.

One of the objects of this invention is to provide high-speed lens grinding apparatus having a rotating spindle for supporting a lens blank in a grinding position, which can be rapidly started and stopped with a minimum of power, and which can be longitudinally displaced while being driven at high speed.

Another object of the invention is to provide for an apparatus of the character described a lightweight clutch mechanism for engaging and disengaging the spindle with the power source supplying the driving torque.

It is also an object to provide a braking mechanism for a high-speed grinder of the type set forth, the brake mechanism operating independently of the power source supplying the driving torque to the spindle and applying braking power to the spindle to stop the rotation thereof rapidly.

Still another object is to provide in a high-speed lens grinder a hollow spindle adapted to be rotated about its longitudinal axis at high speed and also mounted for reciprocating motion while being rotated, the clutch mechanism operating to engage during the entire movement of the spindle in one direction and disengaging when the spindle moves in the opposite direction, and having a brake mechanism operating to stop the rotation of the spindle when the clutch mechanism disengages.

Another of the objects resides in the provision of a protecting device which operates to prevent abrasive particles from entering the bearing surfaces of the spindle.

Further objects and advantages of the present invention will be apparent from the following description, reference being had to the accompanying drawings wherein a preferred form of embodiment of the invention is clearly shown.

In the drawings:

Fig. 1 is a front elevational view of one form of lens grinding apparatus, the operating handle being shown in the raised position;

Fig. 2 is a vertical sectional view taken on the line 2—2 of Fig. 1; and

Fig. 3 is a top elevational view, partly in sections, taken on the line 3—3 of Fig. 1, and illustrating the operating handle in the down position.

Referring further to the drawings, the quill housing 10 is formed with a substantially circular cross section having a central bore therein. This housing is also formed with an integral bracket 55

portion 13 having a flanged edge 14 by which it can be mounted in operating position, as by means of the bolt and washer indicated at 15 in Fig. 2 for example.

5 Housing 10 provides an outer supporting member for the spindle sleeve 17. This sleeve, which can be formed from a piece of steel tubing if desired, is reciprocably mounted within the housing 10 as seen in Fig. 3. The sleeve is formed 10 with an elongated keyway 18 at one side thereof. A key 19, secured to the housing 10 with a cap screw 20, is received within this keyway to prevent the sleeve 17 from rotating relative to the housing 10. To provide for raising and lowering the sleeve 15 within the housing, on the opposite side from the keyway 18, teeth 22 are cut to form a rack cooperating with the pinion 23. The pinion is 20 in turn mounted upon the shaft 24 and driven by means of the feed lever 25 and handle 26 in the usual manner.

The spindle 30 is rotatably mounted within the sleeve 17. This spindle, which is formed with a central bore 31 extending from end to end, seats 25 at its upper end within a tapered roller bearing 32 retained within the upper end of sleeve 17. At its upper end the central bore 31 is enlarged and threaded. The tapered end of a nose piece 33 is fitted into the enlarged bore. Nose piece 35 is also provided with a central bore, aligning with the bore 31, and of sufficient diameter to receive the hollow stemmed and threaded bolt 36.

At the lower end of sleeve 17, the spindle 30 is provided with a ball bearing 40 seated against 30 a shoulder formed therein. This bearing is retained in position by the nut 41 and adjusted by means of the nuts 42. With this construction, it will be readily apparent that the spindle 30 is free to rotate relative to the sleeve 17.

Closing the lower end of housing 10 is a pulley 45 sleeve 45 connected thereto by means of a set screw 46 and formed with a depending collar upon which the pulley 47 is mounted. The sleeve 45 and pulley 47 are formed with central bores 45 therein through which the spindle 30 extends as shown in Fig. 2. A ball bearing 48 seats against the shoulder on the pulley sleeve collar, being retained in position by the U-shaped retainer ring 49. A set screw 51 is received through the center of the pulley belt groove to aid in retaining the bearing in position. At the upper end of the pulley a passage 52 having a pressure type of lubrication fixture 53 fitted therein communicates with the bearing 48 for the purpose of supplying a lubricant thereto. An oil seal 54 is provided 50 to retain the lubricant when applied under pres-

sure. The pulley 47 is thus mounted for free rotation relative to the sleeve 45. A driving connection with the spindle 30 is obtained through a clutch mechanism.

The clutch mechanism has a cup-shaped clutch drum 57 of aluminum connected to the bottom of the pulley 47 by means of dowels 58 and flat-headed machine screws 59. This drum is provided with a central aperture through which the spindle 30 passes freely. The annular side walls of the drum 57 are tapered downwardly from the top and are adapted to engage with similarly tapered side walls of the clutch shoe 61.

The clutch shoe 61 is also formed of aluminum and is provided with a central sleeve portion 62 through which the spindle 30 is received. The annular side walls of this shoe have a leather clutch facing 63 riveted thereto. Thus when the shoe 61 is moved up into the position illustrated in Fig. 2 the clutch facing 63 engages with the inner surface of the side walls of the drum 57. Since the drum 57 is rotated by the driven pulley 47, the shoe 61 being in engagement with the drum is also driven. When the shoe is moved down out of engagement with the drum the driving connection therebetween is broken.

In order to drive the spindle 30, the lower end thereof is formed with a pair of oppositely disposed keyways 65 and 66. These keyways extend upward along the spindle and terminate in the shoulders 67 and 68. The interior of the sleeve 62 is similarly provided with keyways so that the shoe 61 can be connected thereto. A pair of oppositely disposed keys 70 being received in these keyways and retained in position by means of a pair of flat-headed machine screws 71 for this purpose. With this construction, the spindle is free to move up and down vertically relative to the sleeve 62 i. e., shoe 61. It is rotated therewith, however, by means of the driving connection effected through the keys 70.

At its lower end the sleeve 62 is slidably received within the retainer sleeve 75. This sleeve, through which the spindle 30 also extends, is locked thereto by means of the key 76 and set screw 77. The coiled clutch spring 78 is retained in position by this sleeve with one end seating against the underside of the clutch shoe 61 as seen in Fig. 2. Thus when the spindle is raised the sleeve 75 moves upward relative to the sleeve 62. Spring 78 is compressed until further upward movement causes the shoe 61 to move up into driving engagement with the drum 57. This construction provides one of the features of this invention. Thus when the compression of spring 78 is properly adjusted a slight upward movement of the spindle will engage the clutch members 57 and 61 and a rapid starting of the spindle rotation is obtained. Further upward movement of the spindle can also be obtained where it is desired to vary the vertical movement of the spindle relative to a work piece supported above the upper end of the spindle for example. As will be readily apparent from the construction disclosed, such further upward movement only tends to compress the spring 78 to a greater extent and maintains a tighter engagement between the drum 57 and the shoe 61. Thus substantial vertical movement of the spindle can be obtained without effecting the driving engagement between the clutch members 57 and 61.

To provide for a rapid stopping of the fast rotating spindle when the clutch drum and shoe

are disengaged, an annular brake ring 80 is provided. This ring is mounted on a pair of brackets 81 and 82 secured at their upper ends to the housing 10 by means of cap screws. The ring is secured to the lower ends of the brackets by means of cap screws and is maintained in spaced relation with respect to sleeve 75 and the lower end of the clutch shoe 61 thereby. A ring of brake lining 83 is secured to the upper side of ring 80 by means of rivets. Thus when the clutch members are disengaged, the shoe 61 moves down and the lower edge thereof engages with the brake lining 83 and the rotation of the spindle stopped. It is to be noted in this construction that another of the features provides for downward vertical movement of the spindle without disengaging the clutch members and applying the brake until the shoulders 67 and 68 move down sufficiently to strike the keys 70. Any further downward movement of the spindle disengages the clutch members by forcing the shoe 61 away from the drum 57 and into contact with the brake ring 80. A very rapid braking action is thereby provided which enables the operator to wait a minimum of time only for the spindle to stop rotating when changing operation or work pieces, for example.

To complete the assembly, this high-speed grinder is provided at its upper end with a pan base 90 which is mounted over the end of sleeve 17, being secured thereto with a set screw 91. This base is formed with a central opening through which the upper end of spindle 30 projects. It is also provided with a passage 92 communicating at its inner end with the bearing 32. A fitting 93 is mounted at the outer end of this passage to provide for forcing lubrication under pressure into the bearing. An oil seal 94 is provided to prevent the loss of lubrication along the exterior surface of the spindle at the top thereof. The pan base 90 is thus free to move vertically with the sleeve 17, but does not rotate with the spindle 30. Supported on the pan base is the water pan 96 which is formed with a central opening therein through which the upper end of the spindle extends as seen in Fig. 2. This opening is of sufficient diameter for the pan 96 to seat down on the annular shoulder 97 formed at the top of the pan base 90. This shoulder is recessed on the interior adjacent the central bore to provide for mounting the oil seal 94.

To further protect the bearing 32 and rotating surfaces at the upper end of the spindle against the entrance of abrasives carried in the liquid flow from the work operations performed within the water pan, a cap or flinger 100 is provided. This flinger is provided with a central opening therein and is received over the upper end of the spindle, being held in place by means of the set screw 101. The flinger is formed with annular depending side walls 102 which extend down almost to the shoulder 97. These walls are maintained in spaced relation to provide sufficient clearance for their rotation with respect to the upwardly projecting shoulder 97 of the pan base 90. Since these walls overhang the shoulder 97, which provides through the oil seal 94 the only entrance from the interior of the pan 96 to the bearing 32, and since they are rotated at a high rate of speed with the spindle 30, they tend to fling the abrasive particles outwardly and away from the inner rotating surfaces. Such construction has been found to increase the useful life of the machine very considerably, the machine requiring less servicing and operating over longer

periods of time under adverse conditions with fewer repairs necessary.

A stop rod 105 having a centrally positioned and elongated slot 106 formed therein is threadedly connected at its upper end to the pan base 90. At its lower end this rod, which is received within a bore 107 formed in the projecting boss 108 in the lower part of housing 10, is provided with a brake shoe holder 109, Fig. 1. At the upper end rod 105 is guided through the bifurcated boss 110 formed as an integral part of the housing 10, Fig. 3. An adjustable stop member 112 is bolted to the rod 105 to provide for controlling the amount of vertical movement effected by the sleeve 17. The upper edge of the stop is adapted to strike against the under surface of the projection 110, while the under side of the stop in turn strikes against the upper surface of the boss 108. The movement of the sleeve 17 can thus be adjustably controlled as desired.

To further facilitate operation of the apparatus, a pulley 120 is mounted on the pinion shaft 24. A weight can be attached to this pulley to facilitate the raising and lowering of the handle 26 and the connected sleeve 17.

In operation, a vacuum fitting can be attached to the lower end of the spindle 30 for applying suction action through the bore 31. A vacuum type of holder for the lens blank is then mounted and retained by the suction action upon the nose piece 35. Then the operating handle 26 is raised and lowered by the operator to bring the lens holder into and out of contact with the tool being used to process the lens blank. Such movement of the handle in one direction rotates the pinion shaft 24 and pinion 23 to raise the sleeve 17. Movement in the opposite direction reverses the rotation of shaft 24 and lowers the sleeve 17. The upward movement of the sleeve 17 in turn raises the spindle 30, which is connected thereto with bearings, and which permit rotation of the spindle relative to the sleeve.

To provide for the rapid starting of the spindle 30 to rotate about its longitudinal axis, driving torque is transmitted from the pulley 47 connected to a power source. This pulley is directly connected to a clutch mechanism comprising a drum 57 and a shoe 61. The pulley and drum are mounted for free rotation with respect to the spindle 30. The clutch shoe is keyed to the spindle. Thus when the drum and shoe are engaged the spindle is driven, and when these clutch members are disengaged driving torque is no longer transmitted to rotate the spindle.

The drum 57 is driven constantly and the shoe 61 moved into and out of driving engagement therewith by raising and lowering the spindle 30 as desired. Since the spindle is free to move vertically, but not rotationally, with respect to the clutch shoe 61, the retainer sleeve 75 and spring 78 provide for vertical movement both up and down, within predetermined limits, while the clutch members are engaged and the spindle rotating at full speed.

In order to provide for rapid braking to stop the spindle from rotating after the clutch members are disengaged, a brake ring 80 is mounted in position beneath the clutch shoe 61. Thus when the operator causes the spindle to move down sufficiently to disengage the clutch members the lower edges of the shoe 61 come in contact with the brake ring 80 and the rotation of the spindle is stopped.

It will be apparent from the above description that there is provided an efficiently operating apparatus particularly adapted for lens grinding operations. Both rapid starting and stopping of the spindle rotation are effected, the mass of the parts involved in these operations being relatively light. Thus the motor supplying the driving torque for rotating the spindle at high speed does not have to be started and stopped when it is desired to similarly control the operation of the spindle. The brake operates against only the mass of the hollow spindle and aluminum clutch shoe 61 when applied. It is also only necessary to move these same members when the clutch members are engaged and the spindle rotated. Furthermore, when the clutch members engage to drive the spindle, the spindle can be moved vertically upward without disengaging the clutch. Also, when the spindle is moved in the opposite direction the brake mechanism is applied to stop the rotation. There is also provided a flinger which prevents abrasive particles from entering the bearing surfaces from the upper end of the spindle.

While the forms of embodiments of the present invention as herein disclosed constitute preferred forms, it is to be understood that other forms might be adopted, all coming within the scope of the claim which follows.

We claim:

A lens grinding apparatus, in combination a spindle housing, a spindle sleeve reciprocably mounted within said housing, a spindle rotatably mounted within said sleeve, rack and pinion means connected to said sleeve to provide for reciprocating said spindle, a pulley rotatably mounted relative to said spindle for receiving a driving torque from a power source, a clutch drum connected to said pulley and a clutch shoe having a slidale connection with said spindle, said drum and shoe being constructed and arranged to move into driving engagement with respect to each other upon longitudinal movement of the spindle in one direction and out of such engagement upon similar movement of the spindle in the opposite direction, said slidale connection providing for said engagement of the shoe with the drum and thereafter continued longitudinal movement of the spindle in either direction with the shoe and drum remaining in engagement, and a brake ring positioned to engage with said clutch shoe when the latter moves out of engagement with said clutch drum to provide for stopping the rotation of the spindle upon longitudinal movement thereof in said opposite direction.

ROBERT E. ALLEN.
